CLAIM

The ornamental design for a cardiotomy reservoir with filter, substantially as shown and described.

DESCRIPTION

FIG. 1 is a front elevational view of a cardiotomy reservoir with filter showing my new design;

FIG. 2 is a right side elevational view of the cardiotomy reservoir with filter shown in FIG. 1;

FIG. 3 is a rear elevational view of the cardiotomy reservoir with filter shown in FIG. 1;

FIG. 4 is a top plan view of the cardiotomy reservoir with filter shown in FIG. 1; and

FIG. 5 is a bottom plan view of the cardiotomy reservoir with filter shown in FIG. 1.
